FULL FASHIONED KNITTING MACHINE
WITH PICOT MECHANISMKenneth Howie, Norristown, Pa., assignor to
Wildman Mfg. Co., Norristown, Pa., a corpora-
tion of Pennsylvania

Application March 3, 1932, Serial No. 596,642

46 Claims. (Cl. 66—96)

The invention consists in the features, and combination and arrangement of parts hereinafter described and particularly pointed out in the claims.

5 The invention is illustrated as incorporated in a form of full fashioned knitting machine such as that disclosed in an application for Letters Patent of the United States filed by Kenneth Howie and Charles C. Krieble, dated February 10, 1932, Serial No. 590,942.

In the drawings

Figure 1 is a front view of the upper portion of the machine embodying the invention.

15 Figure 2 is a view looking at the machine from the right hand side thereof.

15 Figure 3 is a plan view of a portion of the machine.

Fig. 4 is an enlarged detail sectional plan view of a portion of the picot mechanism.

20 Fig. 5 is an enlarged detail elevation of the same mechanism.

Fig. 6 is an enlarged detail skeleton view taken from right end of machine, showing the retrograde pawl mechanism and means for making inoperative the narrowing screw controlling the 25 yarn carrier stops.

Fig. 7 is a sectional plan view taken on line 7—7 of Fig. 6.

Fig. 8 is a detail.

30 Fig. 9 is an enlarged transverse section through the picot bar and associated mechanism, attached to the narrowing frame taken on line 9—9 of Fig. 1.

Fig. 10 is a similar view taken on line 10—10 of Fig. 1.

Fig. 11 is an enlarged detail of the mechanism for operating the front narrowing screw.

Fig. 12 is an enlarged detail of the pawl and ratchet mechanism on the pull-band drum.

40 Fig. 13 is a view looking from the rear of the machine of the reciprocating driver for the endless bands for moving yarn guides along the needle row, said view showing parts in section.

45 Fig. 14 is a view substantially on the line 14—14 of Fig. 13.

Picot mechanism

The picot mechanism includes a picot bar 1 having points 1a mounted on a rock shaft 2 by arms 3 fixed to said shaft.

50 This picot bar is adjusted to operative position by swinging it down by hand from an elevated position, so that its transfer points stand over the upper ends of the needles and in line therewith.

There is a picot transfer point for every other needle.

The rock shaft 2 which carries the picot bar is journalled in bearings 4 on the vertically swinging fashioning frame 47 and is under tension of a 5 coil spring 5 tending to rotate the rock shaft to swing the picot bar upwardly to its idle position which is through an arc of 180° from its low or working position, the picot points then pointing upwardly instead of downwardly. The spring 5 10 also urges the rock shaft together with the picot bar towards the right Fig. 1. The bar is held down in its operative position by a clutch collar 6 on the end of said rock shaft engaging a clutch member 7 fixed to the frame bearing 4 and the 15 spring 5 as above intimated tends to keep the clutch members engaged to hold the picot bar down. The clutch has its teeth of such extent that the rock shaft with the picot bar can have limited lengthwise movement without causing the 20 clutch members to disengage and the picot bar to rise to idle position. This limited lengthwise movement is sufficient for the picot points to transfer stitches from the needles with which they initially align to adjacent needles. The 25 picot bar being mounted in the narrowing frame 47 the transfer of stitches takes place in the same general manner as the transfer of stitches in narrowing, that is to say the fashioning or narrowing frame goes down, takes the stitches from 30 the needles onto the picot points, then rises, the picot bar is then shifted lengthwise and upon the next vertical movement of the fashioning frame the stitches are transferred to the needles intended to receive them.

35 The limited lengthwise movement of the picot bar to the left is derived from the right hand block 44a of the narrowing points 44. For making the picot this block is given a leftward movement the distance of one needle space instead of two needle spaces as in narrowing and in order to make any desired number of courses of picot the 40 said narrowing point carrier or block is given a limited reciprocating movement along the needle row each stroke, left and right, being the distance of one needle space.

45 In moving leftward the right hand carrier block 44a, Fig. 1, which has a stud 9 bearing on the end of the bracket 10 fixed to rock shaft of the picot bar, moves said rock shaft with said bar 50 leftward against the tension of the spring 5 and upon the movement of the narrowing point carrier to the right the spring 5 follows up and moves the rock shaft with the picot bar rightward. It will be understood that the narrowing 55

point carrier at the left end of the needle row has no stud to contact with the picot bar mechanism and hence does not participate in the operation of the picot bar lengthwise. It will be observed from Figure 1 that the carriers 44a for the narrowing points occupy positions out beyond the ends of the picot bar and hence out beyond the positions ordinarily occupied by these carriers when they are ready to effect the narrowing 10 of the fabric. These extreme outward positions are assumed by the narrowing point carrier by the operation of the hand crank 44j, which is used to reset the narrowing points, after a stocking is finished, into position for making the next 15 stocking, only in this present form of machine, involving the picot mechanism, the narrowing point blocks are set farther outwardly than when the narrowing points are to do only narrowing. These extreme outward positions of the narrowing 20 points i. e. out beyond the ends of the picot bar may be referred to as their idle positions in the sense that the narrowing points when in these positions cannot perform narrowing action. The carrier of the right hand set of narrowing 25 points, however, is utilized as described herein while in this so called idle position in the formation of picot.

The movement of the narrowing point carrier inwardly towards the centre line of the machine 30 and we have here particular reference to the leftward movement of the right hand narrowing point carrier, is due to the step by step rotary movement of the screw shaft 44b derived through the gears 44c, 44d, on shaft 44x, pawl and ratchet 35 44f, 44g, drum 44', band 44e, lever 43g and cam 43h on the main cam shaft a and it will be understood that for narrowing this leftward movement of the narrowing point carrier is of a length equal to two needles, but when the movement of the 40 narrowing point carrier is utilized for the automatic operation of the picot bar it will be understood that the movement of said narrowing point carrier must be limited to only one needle space. For deriving this limited movement through the 45 same pawl and ratchet mechanism above described which, for narrowing, gives the movement equal to two needle spaces, a shield 11 is employed so that the pawl 44f in its regular reciprocating movements will turn the ratchet 44g only one tooth instead of two teeth and this 50 limited movement of the ratchet will result in a leftward movement of the right hand narrowing point carrier 44a to the distance of one needle space instead of two as ordinarily used in narrowing. Contact of this pin with the adjusted 55 shield will hold the pawl from engaging the ratchet during the initial movement of said pawl.

This shield 11 is mounted loosely on the shaft of the ratchet and has its edge 11a in the path 60 of a pin 12 on the pawl.

When the picot bar is in lowered position ready to act, the shield is held in its effective position to prevent the pawl 44f from taking more than one tooth by an arm 13 having a pin 14 engaging 65 a notch in the body of the shield. This arm 13 is fixed to a rock shaft 15 journalled in the fashioning frame, said rock shaft being under tension of a spring 16 which moves the shield into effective position to make the pawl take only one tooth. This action takes place when the picot 70 bar is down in operative position.

The said rock shaft 15 has an arm 17 which when the picot bar is in its raised or idle position will be operated by the bracket 17a on the rock 75 shaft 2 which carries the picot bar so that the

shield controlling rock shaft 15 will be turned in opposition to its spring and the shield will then be withdrawn so that the pawl 44f can then operate the ratchet, the space of two teeth for regular narrowing operations. In other words 5 this same pawl and ratchet mechanism serves both during the making of picot and during narrowing, but it is varied in its action so that for making picot it moves the narrowing point carrier and hence the picot bar one needle space leftward, Fig. 1, while for narrowing it will move the narrowing point carrier two needle spaces towards the middle of the needle row.

As before stated any desired number of picot 10 courses may be formed and for this purpose the narrowing point carrier 44a is moved back and forth i. e. leftward and rightward so that the picot bar will be reciprocated the distance of one needle space, the leftward movement of the bar being due to the pushing action thereon of the 15 right hand narrowing point carrier, and the right hand movement being due to the follow up action of the spring 5 when the narrowing point carrier moves outwardly the distance of one needle space. This outward or return movement of the narrowing 20 point carrier is due to the pawl 46 and ratchet 25 45 giving a retrograde movement to the screw shaft each time the fashioning frame 47 moves down and up. This action is similar to that 30 which is performed when fashioning the heel tabs, said pawl 46 having been set to engage the ratchet 45 for this retrograde action of the screw shaft. This pawl 46 is pivoted to the side frame of the machine at 46a and it is urged towards the ratchet 35 et by the spring 46g.

In the present form of the machine involving the picot mechanism there is mounted on the rear of the frame bar 46p, Fig. 5 which extends across the fashioning frame 47 a rock shaft 18 to control the position of the pawl 46 in relation 40 to the ratchet 45. The pawl 46 is slotted lengthwise as at 46a'. It receives in its slot a pin 46c from an arm 46d on a short rock shaft 46e which is mounted in one of the links 46f which operate the fashioning frame 47 vertically. This rock 45 shaft has on its inner end a depending arm 46g provided with a pin 19 engaged by the notched end (see dotted lines Fig. 10) of a latch 20 attached to one end of the rock shaft 18 at the back of the said frame bar 46p. Said rock shaft is 50 under tension of a coil spring 22 tending to keep the notched end of the latch down on the pin to hold the short rock shaft which is mounted in the link against the tension of the spring 46g' of pawl 46 in such position that its outer arm 46d will 55 keep the pawl 46 away from the path of the ratchet 45 as this moves up and down with the fashioning frame. When, however, the machine is set for making picot a cam or member 1b on the carrier block 44a of the narrowing points 60 will act against a block 23 on the rock shaft 18 and turn the same slightly so as to lift the latch 20 from pin 19 of arm 46g whereupon the rock shaft 46e mounted in the link 46f will no longer hold the pawl 46 back against the tension of its spring 46g' but on the contrary the pawl 46 under the action of its spring will move into the range of bodily movement of the ratchet 45 upwardly 65 with the fashioning frame 47 so that the screw shaft 44b will be turned backwardly to retract the narrowing point carrier outwardly. The picot bar under the pressure of the spring 5 will follow this rightward or outward movement of the right hand narrowing point carrier 44a and will thus 70 75 80 85 90 95 100

assume position for beginning the formation of the next picot course.

The block 1b of the point carrier 44a has bevelled ends 1b' and block 23 has bevelled corners 23b to permit a camming action of block 1b thereon.

The rock shaft 18 at the back of the cross bar 46p has a second block 23a thereon near its inner end, the purpose of which is to control the pawl 46 in a manner above described so that when the narrowing point carriers are set inwardly along the screw shaft 44b to their positions for narrowing the heel tabs the right hand narrowing point carrier will come against this inner block 23a and the pawl 46 thereby will be set in position to perform the retrograde movement of the screw shaft for moving the transfer points one needle space outwardly, it being understood that at this time the inward movement of the narrowing point carrier is two needle spaces instead of one.

The block 23a has a bevelled corner 23a' to receive a camming action from shoulder 1b' of the block 1b, Fig. 4.

After the picot has been formed the narrowing points must be moved from their outward positions above described beyond the ends of the picot bar inwardly into position for narrowing. At the termination of the picot formation the main cam shaft which had been shogged to the right for bringing the cam 43h into line with the roller of lever 43g is restored to its position at the left for knitting. This action throws the cam out of line with the said roller and in order that the narrowing point carriers may be automatically set inwardly along the screw shaft 44b into position for narrowing it is necessary to again bring the roller of lever 43g and cam 43h into operative relation. This is done by shifting the roller into line with the cam. For this purpose a cam 24 is mounted on the yarn changer shaft b. This cam has a projection 25 on its side face which operates an arm 26 on a rock shaft 27 mounted on the outer side of the right hand frame or standard of the machine.

This rock shaft has a depending arm 28 which shifts laterally an arm 29 mounted on a pivot pin 30, which arm in turn shifts the roller of lever 43g into line with the cam 43h so that said lever 43g will be operated and through the connections involving the band 44e and pawl and ratchet mechanism the screw shaft 44b will be turned step by step to move the narrowing point carriers inwardly from their outward positions beyond the ends of the picot bar to their positions for narrowing. In this movement the picot bar will be moved leftward and the clutch 6, 7 will be released by separating the clutch collar 6 from the fixed clutch member 7 and then the spring 5 will turn the rock shaft 2 and raise the picot bar to its upper or idle position. At the same time the rock shaft 15 which controls the position of the shield 11 will be released by the departure of the picot bar from operative position and the spring 16 of said rock shaft will turn the same to withdraw the shield so that then at each feeding movement of the pawl 44f the narrowing points will be set inwardly of the machine two needle spaces as in regular narrowing actions. Pivot pin 30 is pressed outwardly by spring 30a, Fig. 1.

The cam 24 on the yarn changer shaft has a peripheral projection 24a which will restore the pawl 46 to inactive position against the pressure of its spring so that the latch 20 can resume operative position to hold said pawl out of the path

of the ratchet 45 as the same moves up and down with the fashioning frame 47. The connection for doing this includes a lever 31, Fig. 6, pivoted to the machine frame and having a spring pin 32 to be set or pressed upon by the peripheral projection 24a on the said cam 24. This lever is connected by a link 33 with the pawl 46. The hook of the pawl 46 and the relation of the teeth of the ratchet thereto is such that although the connections are set by the action of the cam under pressure by reason of the employment of the spring pin, said connections will not be able to move the detent to inactive position until, in the downward movement of the fashioning frame, the engaged tooth of ratchet 45 will leave the hook of the detent 46 so as to release the same whereupon the reaction of the spring pressed pin 32 will push the link 33 leftward and return the pawl 46 to inactive position.

In its idle position the picot bar will be retained by a catch 34 engaging a block 34a fixed on the rock shaft 2. The bar will remain in this position until the machine after completing a stocking is reset for the next stocking, whereupon the catch will be released by hand and the bar will be swung down by hand into position for making picot.

This resetting action for making a new stocking involves operating the hand cranks 44j and 43j to respectively restore the narrowing points to inactive position and to restore the yarn carrier stops to their normal positions, also the picot bar is swung down by hand where it is locked by the clutch 6, 7.

The lever 43g operates two bands, 44e for moving the narrowing point carrier for making picot or for narrowing, and 43e for automatically adjusting the yarn carrier stops as in said application 590,942. These stops are not intended to be operated during the time that the picot is being formed, hence means are provided by which the operation of the band 43e is rendered ineffective during picot formation. For this purpose the cam 24 on the yarn change shaft is provided with a second peripheral cam 24b which at the proper time operates the bell crank lever, 35 pivoted at 36' to the frame bracket so that it will lift and render inactive the pawl 43k pivoted on the side of the loosely mounted drum 43x Fig. 3 on stub shaft of crank 43j operated by band 43e. This pawl 43k when allowed to be effective operates the ratchet km and gearing ko for turning screw shaft 43 so that when this pawl is rendered inactive said screw shaft will not be operated and the yarn carrier stop mechanism will remain unaltered as to the disposition of its stops during picot formation. The cam 24b is of such length that it will maintain the pawl 43k out of operation and therefore the yarn carrier stops are at rest until the narrowing points have been restored from their so called idle positions beyond the ends of the picot bar, inwardly into position ready for normal narrowing operations. That is to say, during the time that the projection 25 on the cam 24 is acting on lever 26 and holding the shifting roller in line with the cam 43h for the movement of the narrowing points inwardly the cam 24b remains in action against lever 35 and the pawl 43k is thus held out of operation with the carrier stops at rest.

The yarn carrier stops are mounted on brackets 36 which latter are adjusted by the screw shaft 43. In Figs. 1 and 2 the cam 47a is for operating the connections 47b, 47c, 47d and 46f which work the fashioning frame 47 during both picot and

narrowing formation. At 50, 51 are shown parts of the shogging cam for the main cam shaft.

A guard is arranged at A to protect the picot points when raised to idle position.

5 The yarn change shaft has thereon cam means such as illustrated generally at 40, Fig. 14, for operating selector slides indicated generally at C¹, C³, C⁵, Figs. 13 and 14, which provide abutments to be set selectively in line with slides 31^j mounted on a driver block 31 which is reciprocated by an endless band 30 to which the driver block is secured. This band is reciprocated by a connector extending from the slur cock carrier, as in the application above referred to. The reciprocating driver block 31 carries pawls 31a which, when raised by the cam portions 31h of the slide 31^j, will engage the dogs 34 on endless bands 26 which carry the yarn guides. These yarn guide bands are arrested at the ends of their prescribed lengths of strokes by stops Rs carried by the blocks 36 which are adjusted by the screw shaft 43. The stops are controlled to be set into or out of line with the projections 35 of the dogs 34 by levers 36e mounted on the blocks 36 and controlled by cam means on the yarn changer shaft b.

30 The pawls 31a have frictional engagement with their respective dogs 34, there being one of these for each endless yarn guide carrier band, and when any one of the said carrier bands is arrested by its dog coming against its stop Rs, the pawl will recede downwardly owing to the inclines at 34d, 34c, on the dogs, and the inclined shoulders 31b on the pawls, and thus the driver 35 will pass on to the end of its stroke.

In arriving at the end of its stroke, the appropriate selector slides C¹, C³, C⁵ will have been set by the appropriate cam on the yarn change shaft so that the abutment on this slide will 40 operate the appropriate one of the cam slides 31^j on the driver block 31, and this will lift the corresponding one of the set of pawls 31a so that this will operate, on the reverse stroke of the driver block, that one of the yarn carrier bands 45 which the selective action of the cam on the yarn changer shaft initiates and consummates through the setting of the prescribed selector slide and the operation thereby of the described parts on the driver block 31.

50 I claim:—

1. A full fashioned knitting machine having a picot bar, movably mounted to assume either idle or operative position and narrowing point mechanism for actuating said bar, in a direction 55 lengthwise of the needle row and in which the narrowing point mechanism is adjusted as a consequence of the movement of the picot bar to operative position, into condition for giving said picot bar a movement of one needle space to transfer the stitches from needle to needle, when 60 said narrowing point mechanism is operated.

65 2. A full fashioned knitting machine having a picot bar, movably mounted to assume either idle or operative position and narrowing point mechanism for actuating said bar, in a direction lengthwise of the needle row and in which the narrowing point mechanism is adjusted as a consequence of the movement of the picot bar to operative position, into condition for giving 70 said picot bar a movement of one needle space to transfer the stitches from needle to needle, when said narrowing point mechanism is operated, and in which, as a consequence of the movement of the picot bar back to idle position, 75 the narrowing point mechanism is adjusted into

condition for moving the narrowing points two needle spaces at each action of said mechanism.

3. In a full fashioned knitting machine a picot bar carrying picot points and mounted in the fashioning frame, said bar being movably mounted to assume an idle position removed from the needles, means for automatically moving said bar to idle position, narrowing points and means for automatically moving said narrowing points from an idle position beyond the ends of the 10 picot bar into position for the narrowing action, the initiation of the automatic movement of the picot bar resulting from the movement of the narrowing points from their idle position towards their position for performing the narrowing action. 15

4. A full fashioned knitting machine according to claim 3 in which the picot bar derives endwise motion, for transferring stitches, from one of the carrier blocks of the narrowing points. 20

5. In a full fashioned knitting machine a picot bar having points for transferring stitches, a fashioning frame carrying said picot bar pivotally, narrowing points, means for adjusting the narrowing point carriers to positions out beyond the space in which the picot bar must operate and for automatically moving said point carriers inwardly from their out positions into positions for transferring stitches in narrowing the 30 fabric, a clutch for holding the picot bar down, means for automatically raising the picot bar from working position when released by said clutch, said clutch being released as a consequence of the endwise movement of the picot bar derived from the narrowing point mechanism, the endwise movement of the narrowing point carrier continuing for narrowing after the picot bar has been withdrawn. 35

6. In combination in a full fashioned knitting machine, a fashioning frame, a picot bar mounted in said frame, a rock shaft mounted in said frame and upon which rock shaft the picot bar is mounted to be raised and lowered, spring means for turning said shaft to raise the picot bar, and for pressing said bar lengthwise, a clutch, one member of which is on the rock shaft and the other member of which is attached to the fashioning frame, said clutch holding the picot bar down against the pressure of the spring means, narrowing point carriers, a screw shaft for adjusting said carriers, said carriers while the picot bar is down, occupying positions beyond the ends of said bar, one of said narrowing point carriers moving the picot bar lengthwise, to transfer stitches when said carrier is moved from its outward position inwardly along the needle row, and for releasing said clutch so that the spring then will move the picot bar to its idle position, the screw shaft thereafter continuing to move the narrowing point carrier to its normal position for narrowing, substantially as described. 50

7. In a full fashioned knitting machine, narrowing point carriers, picot point carrying means, a screw shaft for operating said narrowing point carrier and said picot point carrying means along the needle row for the formation of picot and for moving said narrowing point carriers for narrowing following the automatic withdrawal of the picot bar to its idle position, means for automatically effecting withdrawal of the picot bar to idle position as a consequence of the movement of the narrowing points from idle position towards operative position, and means for operating said screw shaft, said last mentioned means being automatically controlled as a consequence of the automatic 70

movement of the picot bar to idle position so that the narrowing movements of the screw shaft then takes place.

8. In a full fashioned knitting machine narrowing point carriers, a picot bar, a screw shaft for operating the narrowing point carriers and the picot bar, means whereby the picot bar is automatically moved to idle position, means for driving the screw shaft including a pawl and ratchet, the normal action of the same operating the screw shaft to move the narrowing point carriers two needle spaces, a means for causing the pawl and ratchet to move the screw shaft for only one needle space as a consequence of the picot bar being in operative position to transfer stitches and means operated by the return of the picot bar to idle position for setting said means in position for effecting a two needle space action of the screw on the narrowing point carriers, substantially as described.

9. In a full fashioned knitting machine a picot bar, narrowing points and operating mechanism for moving the narrowing points and the picot bar automatically along the needle row one needle space when the picot bar is in operative position and for moving the narrowing points two needle spaces when the picot bar is in idle position, means for automatically returning the picot bar to idle position and means operated as a consequence of the said return movement of the picot bar for controlling said operating means for giving a two needle space movement to the narrowing points, substantially as described.

10. A full fashioned knitting machine having a picot bar and a narrowing point carrier and in which the operation of the picot bar along the needle row to transfer stitches is effected by the movement of the narrowing point carrier in a direction lengthwise of the needle row, means to return the picot bar to idle position, the operation of said means being inaugurated by the movement of said narrowing point carrier, the return of the picot bar to idle position operating controlling means which varies the drive mechanism of the narrowing point carrier from a one needle space movement to a two needle space movement.

11. A full fashioned knitting machine having means for automatically adjusting yarn carrier stops for narrowing, narrowing points, means for adjusting said points automatically for narrowing, a picot bar operated in a direction lengthwise of the needle row to transfer stitches by the movement of narrowing points, means for automatically operating the two sets of adjusting means simultaneously for narrowing, and means for throwing the adjusting means for the stops out of operation when the picot is being formed, and a yarn change cam shaft having a cam thereon for operating the throw out means substantially as described.

12. Apparatus according to claim 11 in which the adjusting means for the yarn carrier stops include pawl and ratchet mechanism and a screw shaft and the adjusting mechanism for the narrowing point carrier likewise consists of pawl and ratchet mechanism and a screw shaft, a lever, bands extending from said lever to the pawl and ratchet mechanisms and a cam for throwing the pawl of the stop adjusting mechanism out of operation when picot is being formed, substantially as described.

13. In a full fashioned knitting machine a main cam shaft, means for shogging said shaft for narrowing, a cam on said shaft, a lever hav-

ing a shiftable roller operated by said cam, means operated by said lever for adjusting the narrowing point carriers, means also operated by said lever for adjusting stops for the yarn carriers for narrowing, a subsidiary cam shaft, a cam on said subsidiary cam shaft for shifting said roller to be operated by the cam on the main cam shaft, when the latter is restored to position for knitting and means for throwing the adjusting means of the yarn carrier stops out of operation substantially as described.

14. Apparatus according to claim 13 in which a cam portion on the subsidiary cam shaft throws out of operation the stop adjusting connections, substantially as described.

15. In a full fashioned knitting machine a picot bar movable along the needle row, a narrowing point carrier, means for giving said carrier a back and forth movement along the needle row when the picot bar is in position to make picot, said picot bar being operated in one direction along the needle row by the said narrowing point carrier, and means for automatically moving said picot bar in the opposite direction when the said narrowing point carrier moves in said opposite direction, substantially as described.

16. In a full fashioned knitting machine having a picot bar and a narrowing point carrier, drive means for causing a back and forth movement of the point carrier along the needle row for inaugurating a similar back and forth movement of the picot bar, said drive means automatically moving the narrowing point carrier for narrowing after the picot is formed and the picot bar is set in idle position.

17. In combination in a full fashioned knitting machine, a picot bar, a narrowing point carrier means for moving the said carrier along the needle row in opposite directions during the formation of picot, and in the direction towards narrowing position after the picot is formed, said narrowing point carrier inaugurating the movement of the picot bar in opposite directions along the needle row to form the picot, said movement of the narrowing point carrier towards the center of the machine causing the movement of the picot bar in a corresponding direction and means rendered operative by the last mentioned movement of the picot bar for returning the picot bar to idle position, substantially as described.

18. In combination in a full fashioned knitting machine, a picot bar movably mounted to assume either its idle or operative position, a narrowing point carrier, means for reciprocating said carrier along the needle row when in position out beyond the end of the picot bar for the movement of the picot bar back and forth along the needle row, said carrier, after the picot is formed, moving to its position for narrowing, and in said movement causing the release of the picot bar for its return to idle position and means for returning said picot bar to said idle position automatically, substantially as described.

19. In combination in a full fashioned knitting machine, a picot bar, a narrowing point carrier, a screw shaft for operating the said carrier, which in turn operates the picot bar, means for giving a retrograde movement to the screw shaft for retracting the narrowing point carrier, and means for automatically throwing said retrograde means out of operation upon the completion of the picot, so that the screw shaft can then move the narrowing point carrier for narrowing, substantially as described.

20. Apparatus according to claim 19 in which

the means for giving a retrograde movement to the screw shaft consists of a pawl which is thrown into operative position as a consequence of the setting of the machine in condition for the formation of picot, substantially as described.

21. A full fashioned knitting machine having a picot bar, a narrowing point carrier adjustable to a position out beyond its position for narrowing and out beyond the end of the picot bar, a vertically movable fashioning frame carrying said point carrier and said picot bar, a screw shaft for operating the narrowing point carrier, means for rotating said screw shaft forwardly for moving the narrowing point carrier towards the lengthwise center of the needle row, a pawl mounted on the frame of the machine, a ratchet carried by the fashioning frame to be engaged by said pawl for giving a retrograde movement to the screw shaft for retracting the narrowing point carrier, controlling means for adjusting said pawl to operative position as a consequence of the setting of the parts for making picot, means for automatically throwing said pawl out of operation after picot is formed, said controlling means having a portion to be contacted by the narrowing point carrier for setting said pawl again in operative position during the narrowing of the heel tab, substantially as described.

22. Apparatus according to claim 19 in which the means for giving a retrograde movement to the screw shaft consists of a pawl pivoted on the frame, and a ratchet carried by the fashioning frame which also carries the screw shaft, a narrowing point carrier and picot bar and means for controlling the pawl consisting of a member to be operated by the narrowing point carrier when moved into position for the formation of picot and another member to be operated by said carrier when moved into position for forming the heel tab narrowings and a connection between said members and the said pawl for setting the same in operative position.

23. Apparatus according to claim 19 in which the means for giving a retrograde movement to the screw shaft consists of a pawl pivoted on the frame, and a ratchet carried by the fashioning frame which also carries the screw shaft, a narrowing point carrier and picot bar and means for controlling the pawl consisting of a member to be operated by the narrowing point carrier when moved into position for the formation of picot and another member to be operated by said carrier when moved into position for forming the heel tab narrowings and a connection between said members and the said pawl for setting the same in operative position, said connection comprising a rock shaft carrying said members, a rock shaft having an arm engaging the pawl for holding it in inoperative position, and a latch operated by the first rock shaft for releasing the second rock shaft, together with the pawl, substantially as described.

24. In a full fashioned knitting machine, a pivotally mounted fashioning frame, links for moving the same vertically, a rock shaft mounted in said frame, to have rotary and endwise movement, a picot bar mounted on said rock shaft, a spring for stressing said shaft rotatively and endwise, a clutch for holding said shaft with the picot bar in lowered operative position against the tension of said spring, said clutch being released by an endwise movement of the shaft against said spring, a narrowing point carrier, a screw shaft carried by the fashioning frame for operating the carrier, said carrier when the picot bar is

down in operative position occupying a position at the end of the picot bar, pawl and ratchet mechanism for operating the screw shaft for moving the narrowing point carrier for narrowing, means for automatically modifying the operation of said pawl and ratchet mechanism for turning the screw shaft for moving the narrowing point carrier a distance of one needle space instead of two as in narrowing, said last mentioned means being set to perform said modifying function as a consequence of the picot point carrier being set in position for making picot, said narrowing point carrier when operated one needle space actuating the picot bar a corresponding distance along the needle row against the tension of the spring, a pawl mounted on the main frame for giving the screw shaft a retrograde movement as a consequence of the vertical movement of the fashioning frame, to retract the narrowing point carrier a distance of one needle space, said spring shifting the rock shaft and picot bar to follow up the retrograde movement of the narrowing point carrier, means for adjusting the pawl into position for effecting said retrograde movement as a consequence of the setting of the narrowing point carrier into position for making picot, said narrowing point carrier by a step by step movement actuating the picot bar and its shaft for releasing the clutch whereupon the spring moves the picot bar to idle position, the modifying means for the pawl and ratchet mechanism then restoring the pawl and ratchet operation for actuating the screw shaft to move the narrowing point carrier two needle spaces for narrowing and means for resetting the retrograde pawl in idle position.

25. A full fashioned knitting machine according to claim 24, means for again bringing the retrograde pawl into action for retracting the narrowing point carrier one needle space during the narrowings at the heel tab, substantially as described.

26. A full fashioned knitting machine according to claim 24 in which the retrograde pawl is controlled by a rock shaft movable with the fashioning frame, an arm on said rock shaft having a sliding connection with said pawl, a latch controlling said rock shaft, a second rock shaft on the fashioning frame controlling said latch, said second rock shaft being set to release the latch as a consequence of moving the narrowing point carrier into position for making picot, said modifying means for the pawl and ratchet driver consisting of a shield and a rock shaft on the fashioning frame, controlling said shield and itself set by the picot bar, substantially as described.

27. In a full fashioned knitting machine, a picot bar having points for transferring stitches, a pivotal mounting for said bar allowing it to swing upwardly to an idle position, automatically releasable locking means for holding the picot bar in operative lower position, means for automatically swinging said bar to idle position when the locking means is released and means for releasing the locking means automatically as a consequence of moving the narrowing points from their outward positions inwardly into position ready for narrowing action, substantially as described.

28. In a full fashioned knitting machine, yarn carrier means, adjustable stops for the yarn carrier means, narrowing points, carrier means therefore, a picot bar, means for moving the picot bar to idle position automatically, a cam shaft, means for shogging the said shaft from position for knitting to position for narrowing or picot

- forming, a roller with which a cam on the cam shaft aligns when the cam shaft is shogged into position for narrowing, connections operated by said cam and roller for adjusting the narrowing 5 points and adjusting the stops for narrowing, means for shifting the said roller temporarily into line with the said cam when the cam shaft is shogged back to position for knitting, said roller and the connections leading to the narrowing 10 point carriers then operating the narrowing point carriers inwardly towards each other into positions ready for narrowing operation and means for preventing adjustment of the yarn carrier stops during adjustment of the narrowing points 15 as required in connection with picot formation.
29. Apparatus according to claim 28 in which the means for shifting the cam roller temporarily into line with the cam when the cam shaft is in position for knitting consists of a rotary cam, said cam also carrying the means for throwing out of operation the yarn carrier stop adjusting mechanism, substantially as described.
30. In combination in a full fashioned knitting machine, a picot bar movable in a direction lengthwise of the needle row, a screw shaft, a narrowing point carrier operated by said screw shaft, and means for giving said shaft a rotary reciprocating movement imparting to said narrowing point carrier a back and forth movement along 25 the needle row, during the formation of picot, said carrier moving the said picot bar, said picot bar having reciprocating action under control of said back and forth moving narrowing point carrier substantially as described.
31. In a full fashioned knitting machine, a screw shaft, a narrowing point carrier on said screw shaft, a picot bar, movable lengthwise of the needle row by contact from the narrowing point carrier, means for giving the screw shaft 30 rotary reciprocating movement to move the narrowing point carrier back and forth in a direction lengthwise of the needle row, means for moving the picot bar to idle position, and means for giving to said screw shaft different degrees of rotary 35 movement, said means being timed relative to the positions of the picot bar for moving the narrowing point carrier a distance for making picot when the picot bar is in operable position and for moving said carrier a distance suitable for narrowing 40 with the picot bar in idle position, said picot bar having reciprocating action under control of said back and forth moving narrowing point carrier.
32. A full fashioned knitting machine comprising a narrowing frame having up and down movement, a picot point carrier mounted on said narrowing frame to have movement relative to said frame, to and from operative position, narrowing point carrier operating means in part on the narrowing frame and in part on the main frame for 45 operating said narrowing point carriers both during narrowing and during picot formation, one of said narrowing point carriers moving the picot point carrier lengthwise of the needle row during picot formation, and also for the release of said 50 picot point carrier from means which holds it in working position, controlling devices for the operating means of the narrowing point carrier, said devices being controlled by the picot point carrier to give a different degree of movement to the narrowing point carrier when said picot point carrier is in working position from that when said picot point carrier is in idle position, and also to give a 55 back and forth movement to said narrowing point carriers when the picot point carrier is in working position for making picot, and a step by step 60
- inward movement to said narrowing point carrier along the needle row for narrowing; said controlling devices also changing the movement of the narrowing point carriers for heel tab narrowing, yarn carrier stops, means for automatically adjusting said stops during narrowing actions and means for maintaining said stops in positions of rest during picot formation and during the restoration of the narrowing point carriers from the 65 positions in which they are in during picot formation to position for narrowing and means for initiating said restoration of the narrowing point carriers automatically.
33. A full fashioned knitting machine having narrowing points, a picot bar, yarn carrier stops, a cam shaft which is shifted axially from knitting to narrowing position, connections for operating the narrowing points at proper times by a cam on said cam shaft when shifted to narrowing position, said connections including a shiftable member with a cam for shifting the same after the cam shaft has been returned to position for knitting so that the narrowing points will be restored to position ready to perform narrowing operations, and means for preventing operation of the 70 yarn carrier stops during narrowing or picot formation and during the restoration of the narrowing points to said operative position.
34. In a full fashioned machine, a picot point carrier, narrowing point mechanism operating 75 said carrier in a direction lengthwise of the needle row, said narrowing point mechanism including carriers for narrowing points, said narrowing point mechanism being adjusted, as a consequence of moving the picot point carrier to operative position, into condition for giving the said carrier its prescribed movement along the needle row when said narrowing point mechanism is operated, said narrowing point mechanism, as a consequence of the return of the picot point carrier to idle position, being restored to its previous condition for giving the prescribed movement to the narrowing points for narrowing.
35. A full fashioned knitting machine having a screw shaft carried by a pivotally mounted 80 narrowing frame for operating narrowing point carriers, advancing pawl and ratchet mechanism on said narrowing frame for operating the screw shaft, a picot bar mounted on the narrowing frame and shiftable from operating position at 85 the needle row to an idle position, means on the main frame for operating the pawl and ratchet mechanism, a retrograde pawl on the main frame for operating the screw shaft reversely as a consequence of the upward movement of the narrowing frame, controlling means on the narrowing frame for setting the retrograde pawl in position for operating the screw shaft, said controlling means being in turn controlled by the setting of the narrowing point carrier in position for making 90 picot and being controlled also by said narrowing point carrier when set in position for heel tab narrowing, and means on the narrowing frame for controlling the degree of effective operation of the advancing pawl on the ratchet and screw shaft, 95 said last named means being in turn controlled by the position of the picot bar.
36. A full fashioned knitting machine according to claim 35 in which the controlling means for the pawl and ratchet mechanism and for the retrograde pawl includes rock shafts mounted on the narrowing frame.
37. In a full fashioned knitting machine, a picot bar movable to and from operative position 100 at the needles, means for holding the picot bar

- in operative relation to the needles, means for automatically returning the picot bar to idle position when released from said holding means, means for giving the picot bar a limited movement lengthwise of the needle row while retained by said holding means for the formation of the picot, and for giving said picot bar an additional movement lengthwise of the needle row for releasing picot bar from the said holding means, substantially as described.
38. A full fashioned machine according to claim 37 in which the picot bar is pivotally mounted and the holding means comprises clutch members coaxially arranged with the pivot of the picot bar, said clutch members having movement axially in engaging and disengaging.
39. A full fashioned knitting machine comprising a picot bar movable to and from operative position at the needles, a narrowing point carrier, a screw shaft for moving said carrier, a pawl and ratchet for operating the screw shaft, a shield controlling the operation of the pawl whereby the shaft is turned for moving the carrier through different numbers of needle spaces, a fashioning frame carrying the picot bar and said screw shaft, a rock shaft also carried by said fashioning frame, and a connection from said rock shaft to the shield for controlling the same, said rock shaft being operated as a consequence of the movement of the picot bar to and from operative position.
40. A full fashioned knitting machine comprising a row of needles, a picot bar movable to and from operative position at the needles, a fashioning frame carrying the picot bar, a screw shaft also carried by the fashioning frame, a narrowing point carrier operated by said screw shaft, a ratchet connected to the screw shaft and having movement bodily with the fashioning frame, a pawl mounted on the main frame, adjustable to and from operative position in the path of bodily movement of the ratchet, a rock shaft carried by the fashioning frame and having a slip joint connection with the said pawl, normally holding the same out of line with the path of bodily movement of the ratchet, and means for operating the rock shaft by the narrowing point block to set the pawl in line with the bodily movement of the ratchet when the narrowing point block is adjusted into position for picot formation or for heel tab narrowings, substantially as described.
41. In a full fashioned knitting machine, narrowing point carriers, picot point carrying means, a screw shaft for operating said narrowing point carrier and said picot point carrying means along the needle row for the formation of picot and for moving said narrowing point carriers for narrowing following the automatic withdrawal of the picot bar to its idle position, means for automatically effecting withdrawal of the picot bar to idle position as a consequence of the movement of the narrowing points from idle position towards operative position, and means for operating said screw shaft, substantially as described.
42. A full fashioned knitting machine having narrowing points, carriers therefor, a picot bar automatically returnable to idle position as a consequence of the movement of the narrowing point carriers from idle towards operating position, and means for automatically moving said carriers from idle position out beyond the ends of the picot bar to a position where the narrowing points perform the narrowing operation.
43. A full fashioned knitting machine having a picot bar, means for withdrawing the picot bar from operative position, and a narrowing point carrier which inaugurates the operation of said means to return the picot bar to idle position by the movement of the narrowing point carrier from idle towards narrowing position along the needle row.
44. A full fashioned knitting machine having a picot bar and a narrowing point carrier and in which the movement of the picot bar lengthwise of the needle row to transfer stitches is effected by the movement of the narrowing point carrier, said picot bar being movable to and from operating position, a narrowing screw for operating the said carrier, and means for operating the said screw variably to give said carrier different degrees of movement, said operating means being controlled as to its variable driving capacity by the movement of the picot bar to operative or idle position.
45. A full fashioned knitting machine having a picot bar and a narrowing point carrier and in which the operation of the picot bar along the needle row to transfer stitches is effected by the movement of the narrowing point carrier in a direction lengthwise of the needle row, means to return the picot bar to idle position, the operation of said means being inaugurated by the movement of said narrowing point carrier, substantially as described.
46. A full fashioned knitting machine having yarn carrier stops, a screw shaft for automatically adjusting said stops for narrowing, pawl and ratchet mechanism for operating the screw shaft, narrowing points, a screw shaft for adjusting said points automatically for narrowing, pawl and ratchet mechanism for operating the screw shaft last mentioned, a picot bar operated in a direction lengthwise of the needle row, to transfer stitches, by the movement of the narrowing points, and a cam shaft having a cam thereon for throwing the first mentioned pawl and ratchet mechanism out of operation when picot is being formed.

KENNETH HOWIE.
